INVENTOR:

Bourbon Current

By Attorney.

UNITED STATES PATENT OFFICE.

BOURBON CURRENT, OF PARIS, KENTUCKY.

HAND FENCE-MACHINE.

SPECIFICATION forming part of Letters Patent No. 378,873, dated March 6, 1888.

Application filed July 16, 1887. Serial No. 244,496. (No model.)

To all whom it may concern:

Be it known that I, BOURBON CURRENT, of Paris, in the county of Bourbon and State of Kentucky, have invented a new and useful

5 Improvement in Hand Fence-Machines, which improvement is fully set forth in the following specification and accompanying drawings, in which—

Figure 1 is a perspective view of my portable device for making wire fences. Fig. 2 is 10 a side view of the gages. Fig. 3 is a top view, partly in section, showing the manner of applying the twister to the wires of the fence; and Fig. 4, a side view of the section of the 15 fence.

My device relates to an improvement in machinery for constructing palings and wire fencing; and its object is to provide an improved twisting device which may be easily 20 and efficiently operated by hand-power, and in connection therewith an adjustable gage whereby the spaces between the pickets may be regulated at will, all of which will now be fully set forth in detail.

25 In the accompanying drawings, A represents a slotted disk, made of wrought or cast iron or other suitable material, with three integral radial arms, A', of proper length, which are slightly bent to adapt them to the hands 30 of the operator. The edges of the slots E, where they engage the wires, are rounded in cross-section.

B B are adjustable collars constituting the gage, having openings B' to admit the wire 35 into the twister, and lugs C, which pass transversely through openings C' in the disk A, and are secured by set-screws D.

It will be observed that the gage-collars are each provided with a divergent opening, which openings come into alignment with the twist- 40 ing slot E.

To operate the device, I provide a twister for each pair of wires used in the construction of the fence, and when a new paling is added the twister-gage is placed against the last secured paling and the new paling pressed against the outer gage-collar. A twist is now made which takes a pinching hold on the new paling sufficient to retain it in place, and the operation is then completed. 50

What I claim is—

1. In a portable fence-machine or wire-twisting device for wires, a central disk having a slot and radial arms and provided with adjustable gages on both faces of the disk for 55 regulating the distance between the palings, substantially as herein set forth.

2. In a portable fence-machine, the combination of a central disk or body having a slot and radial arms, with an open ring on each 60 side of the central disk, provided with lugs which pass through the disk, and adjusting-screws to regulate the distance between the palings, substantially as herein set forth.

In testimony that I claim the foregoing I 65 have hereunto set my hand, this 2d day of April, 1887, in the presence of witnesses.

BOURBON CURRENT.
